Primary Examiner — Cynthia M Chin(74) *Attorney, Agent, or Firm* — Law Office of William Gustavson, PC(57) **CLAIM**

The ornamental design for a boating accessory, as shown and described.

DESCRIPTION

FIG. 1 is a perspective top view of a boat accessory embodying my design, the apertures shown in dotted line forming no part of the present invention;

FIG. 2 is a perspective bottom view thereof, the apertures shown in dotted line forming no part of the present invention;

FIG. 3 is a front view thereof;

FIG. 4 is a right side view thereof, the left side view being a mirror image of the right side view;

FIG. 5 is a back view thereof;

FIG. 6 is a top view thereof, the apertures shown in dotted line forming no part of the present invention; and,

FIG. 7 is a bottom view thereof, the apertures shown in dotted line forming no part of the present invention.
